UNITED STATES PATENT OFFICE.

ALCORN RECTOR, OF NEW YORK, N. Y., ASSIGNEE TO RECTOR GAS LAMP COMPANY, OF NEW YORK, N. Y., A CORPORATION OF NEW YORK.

COMBUSTION APPARATUS.

1,144,785.

Specification of Letters Patent. Patented June 29, 1915.

Application filed September 26, 1910, Serial No. 583,776. Renewed May 19, 1915. Serial No. 29,227.

To all whom it may concern:

Be it known that I, ALCORN RECTOR, citizen of the United States, residing at New York city, in the county and State of New York, temporarily residing in the city of Pittsburgh, in the county of Allegheny and State of Pennsylvania, have invented certain new and useful Improvements in Combustion Apparatus, of which the following 10 is a specification, reference being had thereto in the accompanying drawing.

This invention relates to combustion apparatus for any and all uses, especially as heaters, furnaces, etc.

15 The method herein involved is not herein claimed, as it forms the subject-matter of my application Serial No. 583,775, filed Sept. 26, 1910.

The objects of the invention are to improve combustion and to produce a convenient and efficient form of apparatus for various heating and industrial purposes.

20 The invention involves mechanical parts for spraying or jetting into a combustion chamber both a gas or gaseous fuel and combustion-supporting gas, such as air or oxygen.

25 In the accompanying drawings, illustrating the principle of my invention and the best mode now known to me of applying that principle, Figure 1 is a vertical, central elevation of a form of apparatus embodying my invention; and Fig. 2 is another view, mainly in elevation but partly in vertical section, of another form of apparatus embodying my invention.

30 In the apparatus, any suitable gas or gaseous mixture may be used, but it is particularly intended for the burning of natural and other gases requiring an especially high percentage of air for perfect combustion.

35 In the drawings, the bunsen 30, having the usual air-controller 30^a, is formed with an enlarged head 31 containing a gas or other fuel chamber. The central portion of the outer wall of this chamber is imperforate at 32 and surrounded by a perforate wall 33, the imperforate and perforate walls 32 and 33 forming what may be considered as the burner-plate or head of a Bunsen burner. The perforations are indicated by 34. Adjacent to the head 31 is a casing 35 containing a combustion chamber, which is 40 separated from the gas or fuel chamber in

the head 31 by said perforate wall 33. The exterior wall of structure 35 which contains the combustion chamber forms a heater; but the whole apparatus may be of any desired shape, contour and size, and adapted for any heating purpose. It may be of any suitable material for any purpose; that is, for heaters, furnaces or the like. This so-called heater-plate is formed with a tubular central air-pipe 36, the end of which rests 45 on the imperforate wall 32, which is preferably opposite the tubular portion of the bunsen. The wall of this pipe 36 is annularly perforated at 37, and the combustion chamber 35 is provided with out-going suction pipes 38 which communicate with a vacuum producing and maintaining device 39, the fan being indicated by 40 and driven by a motor, or in any other suitable manner. In this case, air and gas are mixed in the 50 bunsen and drawn into the fuel chamber 31 by the suction of the vacuum producing and maintaining device; and the gas or gaseous fuel is jetted into the combustion chamber 35 through the perforations 34 during the 55 suction operation of the vacuum producing and maintaining device; and simultaneously with this jetting of the combustible fuel, air is drawn through the pipe 36 and drawn jet-wise through the holes 37 into 60 union with the fuel jets by the suction. By lifting the lid 41 of casing 35, the combustible mixture in the combustion chamber is 65 readily ignited.

70 Of course the arrangement of the described parts may be varied without departure from my invention, depending on the particular uses for which apparatus embodying this invention is intended. The fan is the preferred form of vacuum producing 75 and maintaining apparatus, though any means of artificial suction may be used, and serves to draw air or other combustion-supporting gas to the various points of ignition, when the apparatus is in use, to improve the combustion and to remove products of combustion outwardly from the apparatus.

75 The imperforate portion 32 being placed, in that form of the invention now shown, opposite the delivery end of the bunsen, serves to spread out the inflowing gas into the chamber of the enlarged head 31, so that the perforated wall may be of considerable area, depending on the cross-sectional 80

area of the tube of the bunsen. While the imperforate portion 32 may be perforated in some sizes of the apparatus and for some uses, yet when the wall in portion 32 is imperforate, as shown, it functions as a lateral deflector of the incoming gas, and this is useful in some installations.

The advantage of this type of structure is the intimate mixing and commingling of 10 the gaseous fuel and air or combustion-supporting gas by the jet-like form in which the air is brought in contact with the gaseous fuel. To obtain the best results, both should enter jet-wise into the combustion 15 chamber. Thus two continuous sprays of gaseous fuel and combustion-supporting gas meet and mix in the combustion chamber. As the strong suction makes it possible to direct the combustion-supporting gas in any 20 direction, by an appropriate arrangement of parts, it has an especial value in industrial uses, breaking up the molecules of gas and uniting them with the air at that place in furnaces where needed; the place of melting, for example. Thus the flame and heat 25 are greater at the place of melting than they would be if the gas and air were drawn in bulk form.

In Fig. 2, bunsen 130, having an air-regulator 130^a, leads into casing 131 containing a partition 133 imperforate at 132 opposite the end of the bunsen and perforated at 134 around the imperforate portion. A cover or heater-plate 135^a is provided for 30 casing 131, and is shown provided with a central tubular portion 136 provided around its circumference with a plurality of holes 137 whereby air or other combustion-supporting gas is jetted or sprayed into the 35 combustion chamber 135, the gaseous fuel admitted thereto through the perforations 134 being cross-commingled jet-wise with the air jets. Conduits 138 lead from the 40 combustion chamber to suction fan casing 139 provided with a suction fan 140. Casing 139 has an exhaust port 144. Under the influence of the suction the content of the combustion chamber is partially vacu- 45 umized during combustion, allowing the mixture to be burned to take a continuously attenuated molecular condition, whereby 50 combustion is greatly intensified.

The suction apparatus is operable to secure continuous, uniform suction.

55 What I claim is:—

1. The combination with a fuel chamber of means for supplying the fuel thereto, a combustion chamber, a perforated wall separating said chambers, an air inlet for 60 the combustion chamber, a vacuum producing and maintaining device connected with

the combustion chamber, means for operating the same to draw the fuel and air into the combustion chamber and withdraw the products of combustion therefrom.

2. The combination in a combustion apparatus of a fuel chamber, means for admitting mixed air and gas into the fuel chamber, a combustion chamber adjacent thereto, a perforated wall separating said chambers, 65 means for admitting the combustion supporting gas into the combustion chamber, a vacuum producing and maintaining device connected with the combustion chamber, means to operate the same thereby creating a vacuum in the combustion chamber and drawing the mixed air and gas into the combustion chamber and the combustion supporting gas also into the combustion chamber for further mixture and to withdraw 70 from the combustion chamber the products of combustion all in a rarefied state.

3. The combination in a combustion apparatus of a fuel chamber, a combustion chamber adjacent thereto, means for drawing mixed air and gas from the fuel chamber into the combustion chamber by jets, means for drawing air into the combustion chamber situated in juxtaposition to the fuel chamber, a vacuum producing and maintaining device hermetically connected to the combustion chamber, means for operating the same to positively create and maintain a substantial vacuum in the combustion chamber.

4. The combination in a combustion apparatus of a fuel chamber, a combustion chamber in communication therewith, means for jetting the fuel from the fuel chamber into the combustion chamber, a vacuum producing and maintaining device in communication with the combustion chamber operable to create and maintain a partial vacuum therein, to mix the gas and air and to forcibly draw therefrom the products of 105 combustion.

5. The combination of a fuel chamber with a combustion chamber, a perforated wall separating the chambers means for supplying jets of air into the combustion chamber, a vacuum producing and maintaining device communicating with the combustion chamber operable to forcibly draw air for combustion into the combustion chamber and to forcibly draw therefrom the products of combustion.

In testimony whereof I have affixed my signature in presence of two witnesses.

ALCORN RECTOR.
